FUEL BURNER DIFFUSER

Ralph C. Brierly, Narberth, Pa.

Application January 24, 1947, Serial No. 724,220

12 Claims. (Cl. 158—76)

(Granted under Title 35, U. S. Code (1952),
sec. 266)

1

This invention relates to improvements in diffusers and more particularly to improvements in air diffusers adapted to augment high-speed combustion in the air control registers of fuel burners.

The optimum form of diffuser employed in the past comprises a relatively flat cone or disc stamped in the form of radiating, petal-like blades or spokes and held together at the peripheral edge by a circular band, said band being either stamped and affixed to, or cast integral with, the diffuser. The disadvantages of these forms of diffusers are markedly apparent at high firing rates, when high air pressures and differentials through the registers are being sustained. In such cases, air exiting between the petal-like blades of the diffusers at high velocity tends to blow the flames of combustible away from the furnace face of the diffusers and to extinguish them or tear them apart so violently that some of the combustible is chilled, thereby retard-

10 15 20

The primary object of the invention is to provide a diffuser adapted to permit the heat release per unit area of air-control register throat to be increased above the level practicable with diffusers presently employed.

Another object is to provide a diffuser adapted to augment greatly the degree of intermixture of air and oil at the face of the diffuser so that the flame clings to the furnace side of the diffuser despite hitherto inordinate air velocities.

A further object is to provide a diffuser adapted to disseminate oxidant streams in such a manner that the tendency of the flames to blow away and chill is reduced.

Another object is to provide a diffuser adapted to intermix rapidly oxidant and combustible.

Still another object is to provide a diffuser wherewith the flames tend to adhere close to the front or furnace faces of the diffuser, thereby permitting combustion to be completed in shorter furnace lengths.

A further object is to provide a diffuser wherewith flame equilibrium is obtained proximate the furnace face of the diffuser.

Further objects and advantages of this invention, as well as its construction, arrangement and operation, will be apparent from the following description in connection with the accompanying drawing, in which

Fig. 1 is a plan view of a diffuser, showing a preferred embodiment of the invention;

Fig. 2 is a section thereof taken on the line 2—2 of Fig. 1;

Fig. 3 is an isometric view, partly in section, of a modified form of the invention; and

Fig. 4 is an isometric view, partly in section, of another modified form thereof.

2

Similar numerals refer to similar parts throughout the several views.

The diffuser 11 comprises a frusto-conical member 13, preferably shallow, mounted on the end of a conduit 15, which is adapted to carry combustible to an injector (not shown) seated in the register distance piece 17. A suitable cowl 18 and integral oxidant conduit 20 is provided.

A plurality of spaced and radially disposed nozzles or ports 19 extend from the front or furnace face of the diffuser to the opposite face thereof, the axes of said ports being disposed at an angle to the longitudinal axis of the conduit 15. The axes of said ports can each be disposed at the same divergent angle to the longitudinal axis of the conduit 15, or can be disposed at various angles thereto. Said ports can be divergent in cross-section, as shown, or can be uniform or convergent in cross-section. Further, any desired combination of angular axial disposition and cross-section can be employed without departing from the scope of the invention.

It is apparent that the construction above described is adapted to divide an oxidant stream into a multiplicity of oxidant streams and that employment of appropriate design characteristics provides a desired flame shape, thereby substantially increasing combustion efficiency.

As shown in Fig. 3, an alternative construction adapted to accomplish the same objects provides a plurality of nozzles or conduits 21 extending in diverging arcs from a manifold 23 secured to the furnace end of the conduit 15. Said conduits 21 terminate in a common plane. A plurality of nozzles or conduits 25 extending in diverging arcs from said manifold 23 terminate in another common plane, said conduits 25 and 21 forming nesting polygonal, elliptical or circular patterned groups of air exits, each group approaching or receding from the register distance piece 17. Any desired number of planes of air exit can be employed without departing from the invention.

As shown in Fig. 4, another alternative construction adapted to accomplish the same objects provides a plurality of conduits 27, each extending in a diverging path from a manifold 23 secured to the furnace end of the conduit 15 to a plane disposed at an angle to the longitudinal axis of said conduit 15, and a plurality of conduits 29 each extending in a diverging path from said manifold 23 to another plane disposed at an angle to the longitudinal axis of said conduit 15, said conduits 27 and 29 forming nesting polygonal, elliptical or circular patterned groups of air exits, each group having dimensions that approach or recede from the dimensions of the register distance piece 17. Any desired number of planes of air exit can be

employed, and the conduits 27 and 29 can be of uniform or varying cross-section, without departing from the invention.

Various modifications and changes can be made in the subject device without departing from the scope of the invention.

The invention described herein may be manufactured and used by or for the Government of the United States of America for governmental purposes without the payment of any royalties thereon or therefor.

I claim:

1. A diffuser for oxidant supplied to a fuel burner, said diffuser comprising a plate having a rear face and a front face indented substantially in the form of a cone, said plate having ports therethrough extending from said rear face to said front face, and means for supplying oxidant under pressure solely to said rear face for flow through said ports, each of said ports being positioned in said plate to discharge the oxidant flowing through the respective ports from said front face in a direction diverging from the axis of said cone and lying in a plane passing through the axis of said cone.

2. The diffuser defined in claim 1 including a conduit secured to said plate member for supplying fuel to said front face at substantially the apex of such cone.

3. A diffuser for oxidant supplied to a fuel burner, said diffuser comprising a plurality of nozzles each having an inlet and an outlet, and means communicating solely with said inlets for conducting oxidant under pressure thereto for discharge through said nozzles, said nozzles being so positioned that their outlets lie in the lateral surface of a cone, each of said nozzles being positioned to discharge the oxidant flowing therethrough in a direction divergent from the axis of such cone and towards the base of such cone, the point of discharge of each of said nozzles lying in a plane that passes through the axis of such cone.

4. The diffuser according to claim 3 including means secured to said nozzles for conducting fuel under pressure to a position located at substantially the apex of such cone.

5. A diffuser for oxidant supplied to a fuel burner, said diffuser comprising a member having a plurality of ports therein, and means communicating solely with said ports for conducting oxidant under pressure thereto for discharge through said ports, said ports being so located that they are adapted to discharge in the lateral surface of a cone, each of said ports being positioned to discharge the oxidant flowing therethrough in a direction divergent from the axis of such cone and towards the base thereof, the point of discharge of each of said ports lying in a plane that passes through the axis of such cone.

6. The diffuser according to claim 5 including means mounted on said member for conducting fuel under pressure to a position located at substantially the apex of such cone.

7. A diffuser for oxidant supplied to a fuel burner, said diffuser comprising a plate member having a rear face and a front face, said plate member being substantially in the form of a cone and having ports therethrough extending from said rear face to said front face, and means for supplying oxidant under pressure solely to said rear face for flow through said ports, each of said ports being so positioned in said plate member as to discharge the oxidant flowing therethrough from said front face in a direction diverging from the axis of such cone, the axis of said cone being

normal to a plane passing through a first plurality of said ports and normal to a plane passing through a second plurality of said ports.

8. The diffuser defined in claim 7 including a conduit secured to said plate member for supplying fuel to said front face at substantially the apex of said cone.

9. A diffuser for oxidant supplied to a fuel burner, said diffuser comprising a plurality of nozzles each having an inlet and an outlet opening, and means communicating solely with said inlet openings for conducting oxidant under pressure thereto for discharge through said nozzles, said nozzles being so positioned that their outlet openings lie in the lateral surface of a cone, each of said nozzles being positioned to discharge the oxidant flowing therethrough in a direction divergent from the axis of such cone and towards the base of such cone, the point of discharge of each of a first plurality of said nozzles lying in a plane that passes through the axis of such cone and the point of discharge of each of a second plurality of said nozzles lying in a plane that passes through such axis.

10. The diffuser according to claim 9 including means secured to said nozzles for conducting fuel under pressure to a position located at substantially the apex of such cone.

11. A diffuser for oxidant supplied to a fuel burner, said diffuser comprising a member having a plurality of ports therein, and means communicating solely with said ports for conducting oxidant under pressure thereto for discharge through said ports, said ports being so located that they are adapted to discharge in the lateral surface of a cone, each of said ports being positioned to discharge the oxidant flowing therethrough in a direction divergent from the axis of such cone and towards the base thereof, the point of discharge of each of a first plurality of said ports lying in a plane that passes through the axis of such cone and the point of discharge of each of other pluralities of said ports lying in a plane disposed similarly.

12. The diffuser according to claim 11 including means mounted on said member for conducting fuel under pressure to a position located at substantially the apex of such cone.

RALPH C. BRIERLY.
